UNITED STATES PATENT OFFICE.

KIROKU YAKUSHIJI, OF SAN FRANCISCO, CALIFORNIA.

DESIGN FOR AN ICE-CREAM CORNUCOPIA.

No. 37,759.

Specification for Design.

Patented Dec. 26, 1905.

Application filed October 13, 1905. Serial No. 282,680. Term of patent 14 years.

To all whom it may concern:

Be it known that I, KIROKU YAKUSHIJI, a subject of the Emperor of Japan, residing at San Francisco, in the county of San Francisco and State of California, have invented a new, original, and ornamental Design for Ice-Cream Cornucopias, of which the following is a specification, reference being had to the accompanying drawing, forming part thereof.

The figure is a perspective view of the cornucopia, showing my new design.

I claim—

The ornamental design for an ice-cream cornucopia, as shown.

KIROKU YAKUSHIJI.
